TRAFFIC SIGNALING SYSTEM

Paul P. Horni, Newark, N. J.

Original application July 9, 1937, Serial No. 152,772. Divided and this application May 8, 1939, Serial No. 272,438

5 Claims. (Cl. 177—337)

This invention relates to a traffic control system of the automatic type the signals of which are subject to control by traffic which may be either pedestrian or vehicular, and is a division of my pending application Serial Number 152,772 filed July 9, 1937, now Patent Number 2,157,236 issued May 9, 1939.

Since the flow of traffic usually has a greater density on one street than on an intersecting street, it is necessary to allot more time to the street having the more dense traffic flow to expedite vehicular movement and allay congestion. It is well recognized among traffic engineers that to unnecessarily change the signal lights by indicating a "go" signal to a cross-street to be benefitted thereby, and at the same time set up a "stop" signal to the busy main street, is to aggravate traffic congestion and invite accident. This undesirable feature may be avoided by providing a discretionary signal control operable by traffic on the cross street of an intersection. It is particularly desirable to have this traffic control feature on a side-street which has only occasional traffic. In this way, traffic can flow uninterrupted until a demand is made by a vehicle on the side-street. Traffic signals are frequently installed to take care of such occasional traffic.

It is likewise desirous under certain conditions to indicate neither a definite "stop" nor "go" signal on either street unless a side-street vehicle has demanded the right to cross the intersection by actuating an initiating device. The absence of lights, unless required for traffic control, is a great saving in power consumption over the continuously operated type of traffic control system, reduces the cost for electric light bulbs, since fewer replacements are necessary, curtails labor expense for replacement of the burned out bulbs, eliminates much repair work by prolonging the life of the controller, and reduces the percentage of potential accident periods due to an unsupervised intersection, caused by burned out traffic signal bulbs.

To supervise an intersection which utilizes a traffic control system having the signal lights normally extinguished on both the main and the cross-street, it is necessary to provide devices which may be operated by the traffic to control the signals. These devices which are operated by traffic to initiate a signaling cycle with the equipment present in this application, may be operated by a vehicle or a person. It will be noted that means are provided, for cross-street, surface or trolley cars, as well as automobiles, to

initiate a signaling cycle. The vehicle actuated initiating means, whether mechanical or magnetic, are commonly referred to in the art as detectors.

Applicant's copending application, Serial No. 484,334 is to be distinguished in part from the instant case which has definite and distinct advantages and improvement thereover.

When traffic is active along a main street, which is controlled by normally extinguished traffic signals, experience shows that it is inadvisable to suddenly present a "stop" signal to the moving traffic. To do so, would result in numerous rear end collisions of the vehicles. Consequently, it is expedient to present to moving traffic, a warning or caution indication, prior to displaying a "stop" signal. This gives the traffic an opportunity to adjust itself to the realization that a traffic signal is ahead. While a warning signal is beneficial in the normally extinguished type of traffic signal, it is recognized that the benefits of the warning or caution signal has its limitations, since it attracts the attention of the vehicle driver, but indicates no definite signal.

It is accordingly a primary object of this invention to provide a traffic signal control system of the automatic type which has its operation initiated by traffic demand, to cause at least one signal cycle, which indicates "go" to the moving traffic and "stop" to the cross-street traffic, for a brief interval, then to continue through its normal cycle, part of which cycle indicates "go" to a side street and "stop" to the main or intersecting street, then changes to again indicate "go" to the highway and "stop" to the cross-street, and shortly thereafter, if no demand is made on the cross-street, to lapse into inactivity, giving no signal light in any direction and thereby permitting the regular uninterrupted flow of traffic on the main street, until a future demand is made by a cross-street vehicle or a pedestrian.

The main street, at the intersection, is frequently of such width that it would require many seconds for a pedestrian to negotiate the distance. This lengthy exposure to moving traffic, subjects the pedestrian to a greater danger than if the street were quite narrow. To obviate this hazard, it is provided in this application, and made an object thereof, to allow a greater signaling supervised time for a pedestrian to cross the main highway, than for a vehicle, the shorter vehicle interval, and the longer pedestrian interval, each being initiated by a single independ-

ent actuation of the signal initiating means provided.

Another object of this invention is to provide a system of the type described in which a signal cycle is initiated by a pedestrian or a vehicle approaching the intersection from a cross-street, to control the main street or highway, and the secondary or cross-street, during the signaling cycle, the system having means actuatable during the cross-street "go" interval to cause deceleration of said interval controlling means by traffic, which controlling means is periodically accelerated and again prepared for deceleration by further actuation of the cross-street traffic up to the completion of the cross-street "green" interval.

A further object is to provide a signaling system of the character indicated herein, in which the signaling cycle actuating motor is provided with two windings, one a forward and the other a reversing motor winding, each tending to turn the motor in opposite directions, and being of different torque so that when both windings are energized, the resultant torque on the motor shaft is in a clock-wise direction and when the reversing winding circuit is open, the motor is accelerated, and when the driving winding circuit is open, the shaft motion tends to reverse, in order to properly align the various circuit control cams upon completion of a signal cycle, preparatory to future operations.

A further object of the invention is to provide a traffic actuated signaling system, of the class described wherein the flow of traffic on the cross-street causes a memory device to become operated during the latter part of a signaling cycle to compel a new signaling cycle to become initiated and thereafter to have the traffic signals lapse into inactivity.

Another object is to provide a signaling system wherein a vehicle passing over a detector initiates a signal cycle, a part of which indicates "go" on the street of actuation and "stop" on the intersecting street, said "go" signal being existant for a predetermined interval of time.

While a few of the objects of this invention have been definitely set forth, other and further objects and advantages of the invention will be hereinafter presented and the more novel features thereof defined by the appended claims.

A further object of this novel invention is to provide a signaling system in which a vehicle passing over a detector may initiate a signal cycle a part of which indicates "go" on the cross-street, said "go" interval being enlargeable up to a practical maximum.

For a better understanding of the invention, reference may be had to the accompanying drawing, in which:

Figure 1 is a schematic diagram of the circuit and representative mechanical parts utilized in this invention.

Figure 2 discloses a chart to indicate conditions of contact operating cams and signaling lights at several different intervals of a signal cycle.

Figure 3 is a view generally representative of the positions of the cams and their respective cam rider members and associated contacts in a normal position.

The chart in Figure 2 can be better comprehended by associating same with Figure 3. In the latter figure, cams 1 and 3 are shown with the pivotal cam rider in an inoperated or released position, that is, the cam riders are urged

toward the center of the cam. While any means may be used to hold the cam riders against the peripheral surface of the cams, a coil spring 8, is disclosed as representative of the resilient means which may be employed, one spring being used for each of the cam riders. In the chart, the "0" in each of the squares represents that the cam is in an operated position, that is, the cam rider is urged to its outer extremity from the center of the cam.

In Figure 3, cams 2, 4, 5, 6, and 7 are shown operated. While cam 7 is indicated as being operated, the chart represents that it is not, in fact, operated, but it may be, without altering the operation or effect of the system. The description of operation will bring out that cam 7 contacts are ineffective until cam 3 contacts are closed, which permits the cam 7 contact to be operated anytime prior to the closure of cam 3 contact.

Signaling circuits

The wiring diagram shown in Figure 1 has two conductors indicated by black heavy lines which are marked with a minus and plus or negative and positive symbol to denote simply a source of power. The several cams, shown in Figure 3 and numbered from 1 to 7 inclusive, have centrally pivoted cam riders which have one end thereof normally urged against the riding surfaces of the various cams. The opposite ends of the cam riders, have either one or two contacts thereon to engage cooperative contacts the functions of which will be more definitely explained in presenting the operation of the system.

In Figure 1, the cams are numbered as in Figure 3, and are shown schematically as a numbered circle having a movable arm electrically connected thereto. When the switch 9 is moved to engage contact 10, a circuit is traced from negative battery, through conductor 12, contact 10, switch 9, conductors 13 and 14, cam arm 4A, contact 16 and cam arm 2A. The circuit is divided here and one branch goes through contact 17, signal light G1 (highway green) conductor 30, to positive battery. The other side goes to R2, (cross-street red) conductor 34, to positive battery. Since cams 2 and 4 are normally shown in an operated position when the signaling apparatus is idle, it will be seen that with switch 9-10 closed, the lights would indicate a green or "go" signal to the highway, or number 1 street, and a red or "stop" signal to the cross-street or number 2 street. G1, A1 and R1 represent the green, amber and red lights respectively on the highway, while G2, A2 and R2 represent green, amber and red lights respectively on the cross-street. In this condition with the 9-10 contacts closed, the system would be said to have a normal highway green.

When the signaling control apparatus is set in operation from an actuation by a cross-street vehicle, the motor M rotates. Suitable gearing is provided between the motor and the cam shaft 18 which has securely fastened thereto, cams 1 to 7 inclusive. For purpose of explanation, an arrow pointing in a clockwise direction, is indicated to the left of cam 1 in Figure 3. After the G1 and R2 lights have been energized, subsequent to an initiating actuation, the cam shaft reaches an interval which causes cam arm 2A to restore and engage contact 19 which energizes A1 through conductors 20 and 21. The completion of this circuit causes A1 and R2 to be lighted as represented in position 2. A continued rotation of shaft 18 causes cam 7 to operate, at the

latest, just prior to the operation of cam 3. In position 3, cam arm 4A restores to open circuits to A1 and R2 and to energize R1 through cam arm 3A, contacts 30, conductors 22 and 23, and energize G2 through cam arm 7A, contact 24, conductors 25 and 26, both to connect to positive battery. At this time the cross-street green and highway red lights are energized. A continued rotation brings the cam to position 4, in which cam arm 1A has restored, which deenergizes G2 and energizes A2 through cam arm 1A, contact 27, conductors 28 and 29, to positive battery. In position 5 it will be seen that cam 3 has restored to break the signaling circuit to R1 and A2, substantially simultaneously therewith, cams 2 and 4 operate to again energize G1 and R2.

In position 4, cam 2 operates prior to beginning of period 5 so that the R2 and G1 lights come on together. In the position 2, cam 1 operates prior to beginning of position 3 so that R1 and G2 lights will also come on together. Cams 2 and 1 in positions 4 and 2 respectively, show the latest period of operation to prepare the cam contact for simultaneous operation of the red and green light. The earliest time for cam 2 to operate is just after beginning of period 3, as cam 4 is open. The earliest time for cam 1 to operate is just after beginning of period 5, since at this interval cam 3 is open.

The operation explained immediately above shows the several signaling circuits when the contact set 9-10 is closed with the lights normally having a highway green and a cross-street red. If the switch 9 engages contact 11, it will be noticed the conductor to the negative side of the battery is open. Consequently no current can flow to the lights when the apparatus is idle, yet the lights are prepared for operation through cam arms 2A and 4A, so that the G1 and R2 lights will be energized as soon as a signaling cycle is initiated by traffic. The system would be said, under this condition, to be a "normal out," as used in the field, since no lights are energized yet the intersection is protected and highway traffic may move unobstructed. Immediately upon demand, by pedestrian or cross-street traffic, the operation of the system energizes the G1 and R2 lights, and causes the system to move through its cycle, previously explained, permitting cross-street traffic to control the intersection for a time interval, and then to change the lights in order to restart the highway traffic and stop the cross-street traffic. After the lights have been burning in this position, the signaling system stops its signaling cycle and the lights are extinguished, restoring the system to its "normal out" condition preparatory for further actuation.

Single vehicle actuation

The motor used in the signaling system, has two sets of windings, one set being a driving winding indicated as D which winding rotates the mechanism forwardly, the other winding is for reversing the motor when the driving winding, indicated as R is disconnected, and is used for retarding the forward motion of the motor when both windings are connected. Each set of windings consists of a U shaped group of laminations provided with a main winding and an E shaped group of laminations provided with a phasing winding. These phasing windings are represented in the drawing as P' and P''. The relation between the main and phasing windings is the same as that employed in the single phase AC watt-hour meters. The shaft 32 carries a disc 33 which

revolves intermediate the main and phasing windings. In order to obtain a good driving torque, the main winding is connected in series with the phasing winding and said main windings each being by-passed by a condenser which causes the current through the phasing winding to lead the current through the main winding. The reversing winding is connected with the phasing winding in the same relative polarity of the driving winding, but the main winding of the reversing motor is poled oppositely to the main winding of the driving motor and therefore produces a torque tending to drive the disc in the opposite direction. In order to obtain a smaller torque from the reversing motor than from the driving motor, the capacitor 34 of the reversing winding is of a smaller value of capacitance than the capacitor 35 of the driving winding. The phasing windings are assembled in a common mounting with respect to their main winding and movable about the shaft 32, in axial relation thereto. This permits the simultaneous changing of the motor speed of both the driving and reversing windings. The entire motor is represented by a rectangular dotted enclosure indicated as M.

A single vehicle detector which may be of any convenient type, either magnetic or mechanical, is simply represented by two members 36-36', but it is to be understood that this single detector may be parallel by another detector to take care of traffic on the opposing side of an intersection of a cross-street. It is apparent that the function of the system will be unchanged by using a plurality of detectors connected in parallel. When switch blades 9 and 37 are moved to the right by means of the connecting insulation strip, 38, shown dotted, contact set 9-10 would be closed to energize G1 and R2. The circuit to the reversing motor would then be broken, by the switch blade 37 having moved off its contact 66 which associates itself with the reversing winding of the motor. In this condition, there is a light normally green on the highway. When a vehicle moves over the detector to close the contacts 36-36', a circuit may be traced from negative battery through 38, 36-36', 39, contact 40, switch 41, conductor 42, winding of memory relay M', 50, to positive battery. Relay M' is energized and draws in its armatures 43 and 44, which armatures now engage 43' and 44' respectively.

After the memory relay is energized, a stick circuit is completed for the relay M', and may be traced from negative battery, through 45, armature 44, contact 44', conductor 46, an armature 47 of relay E, and its associated contact 48, conductors 49, 42, winding of relay M', conductor 50, to positive battery.

When the armature 43 of the memory relay M' is energized, the circuit between 43 and 43' is broken which circuit normally energizes the reversing motor over conductor 51, switch blade 52, contacts 71 and 53, and the cam arm 1A, conductor 54, through the windings of R and P'', conductor 55 back to positive battery. The negative battery is normally fed to the armature 43 over conductor 45. The negative battery which is normally on armature 43 of memory relay M' is now engaging 43' and a circuit may be traced from negative battery over conductor 45, armature 43, contact 43'', conductors 56 and 57, to the driving winding D of the motor, coil P', conductor 58 to positive battery.

The motor now having no effect from the reversing winding, can move forward freely and

through suitable gearing, causes the cam shaft and its associated cams to be rotated, starting the lights which move through the various steps of the signaling cycle. Cam 1, according to the chart, may open shortly after the motor starts to rotate, but since contact set 43, 43'' is open, a further opening of the cam arm 1A can have no effect on the reversing winding of the motor. As No. 1 cam operates, opening the 1A-53 contact set, the 1B-59 contact set is closed, placing a parallel circuit from one side of the driving winding of the motor to negative battery. In this case, the circuit may be traced from negative battery, over conductor 60, through contact set 1B-59, conductors 61, 62, 63, 57, windings D and P', conductor 58 to positive battery. This insures the motor to run as long as this cam 1 is operated and protects it from stopping, due to opening of the memory relay energizing circuit and the consequent opening of the armature 43 and its associated contact 43''.

Cam arm 6A is indicated in the chart as being operated but it will be noted that this cam when operated, has its associated contact normally open. The cam arm 5A and its associated contact opens momentarily, that is, the cam 5 is operated periodically. Sometime after the G2 lights have been energized, with the consequent energization of relay E, since G2 and relay E are in parallel, the armature 41 of relay E will be drawn in, which opens the memory relay stick circuit contact set 47-48. The first of the periodic openings of cam arm 5A from its associated contacts, will positively open the circuit to the memory relay to deenergize same. This is obvious since it is apparent that the cam arm 5A will control the energization of relay M for a short time after the opening of the relay E contact set 47-48. A further actuation of the detector 36-36' would have no effect upon the signaling circuits since the momentary energization of the memory relay could not be locked in, since the other possible current paths are open at this instant. Furthermore, the 43-43' contact set, which controls the reversing winding of the motor at certain times, is not controllable by this contact set at this instant, since the 1A-53 contact set is open, due to the operation of cam 1, consequently the motor will run at its normal speed without the effect of the reversing winding until the end of the cycle, when the cam 1 releases to break the energizing circuit of the driving windings to the motor, through the controlling contacts 1B-59. When the cam 1 releases to cause deenergization of the driving winding, it causes contact set 1A-53 to be closed, which now energizes the reversing winding of the motor, since the only other possible controlling contacts 43-43', are closed.

The end of the cycle having been reached and the green light returned to the highway to indicate a "go" signal thereon, said signal will remain there, assuming the controlling contact set 9-10 is still closed. The reversing winding will control the motor and start it to operate in a reverse direction but since the ratchet 64 which is suitably geared to the motor gear train, has a pivotally mounted pawl 65 associated with said ratchet in such a way that the pawl will engage the ratchet shortly after the reversing motor becomes effective, at the completion of the signaling cycle, the effect of the reversing winding will be merely to rotate the motor in a reverse direction until the ratchet 64 is positively gripped by the pawl 65 to prevent further rotation. The

purpose of this ratchet and pawl is to insure the cam shaft 18 of a positive stopping position. The definiteness of this stopping position, is of prime importance when the signal is operating with the lights normally out, because the starting position of the cams which control the highway green and the cross-street red lights, will determine the duration of the burning of these lights before they change to indicate a different signal.

The necessity of this precision of cam positioning at the termination of a cycle with the lights normally deenergized can be shown by stating that in practice, when utilizing the normally out system, drivers of vehicles become accustomed to the length of time that the stop indication is presented to the cross-street before it changes to give them a "go" signal. Consequently, the driver familiar with the intersection will adjust the speed of his vehicle so that he may reach the beginning of the intersection just as the light changes, without the necessity of bringing his vehicle to a full stop, thereby, maintaining the maximum efficiency of speed. If the cam positioning is such that the driver gets the "go" signal on the cross-street before he expects it, there may be no disastrous result, but experience has shown that if he should have the red light stay on the cross-street materially longer than usual, he may, in anticipation of receiving the "go" signal, permit his car to run out into the intersection while traffic on the highway which usually travels at a high rate of speed, is attempting to clear the intersection.

It seems needless to say, that many serious accidents have been caused by drivers running into intersections because of this feature of speed against time. While it is true the operator of a vehicle may wrongly estimate his speed, it is nevertheless also true that drivers do depend on this timing of traffic signals and a serious accident might be avoided, or a life preserved, by permitting a driver to have the proper precise timing that he has a right to expect.

Motor retardation during cross street interval

When there is demand on a side street and only one vehicle crosses the intersection, the driving winding only controls the forward motion of the motor. However, when there are several vehicles, which cross during the green period, there may be more than one effective actuation of the detector. These additional effective actuations cause the reversing winding of the motor to be periodically cut in to periodically have its retarding effect upon the torque of the motor shaft which consequently causes the motor to be slowed down and hold the "go" signal on the cross-street a little longer than the allotted time for a single vehicle to cross the intersection.

Earlier in the application, the operation has been set forth relative to the various circuits necessary for operation by the single vehicle, which single vehicle control was made possible by the switch 37 being moved to the right and opening the circuit to the reversing motor by disassociating switch 37 with the contact 66 of conductor 54. The starting of the signal cycle which has been previously explained, is the same for a single vehicle. As soon as the cross-street green, or G2 lights are energized, the relay E is simultaneously energized, which moves the armature 41 against contact 67, which feeds negative battery to the reversing winding of the motor. The circuit may be traced from the negative battery over conductor 45, armature 44, con-

tact 44', conductor 46, armature 47, contact 67, conductor 68, contact 37-66, conductor 54, R and P', conductor 55 to positive battery. Immediately upon energization of the reversing winding, its consequent effect is to retard the revolutions per minute of the motor. Since the stick circuit over the controlling contact set 47-48 is broken, the stick circuit is now only controlled by the cam arm 5A and its associated contact. As previously explained, the duration of the opening of contacts controlled by cam 5, is periodic, and only open long enough to permit the memory relay M' to become deenergized. As soon as the memory relay is deenergized, due to the opening of the 5A cam arm and its associated contact, the contact set 44-44' is open which causes the current flowing over the conductor 46, contact set 47-67, 68, 37, 66, 54, to the reversing winding, to be interrupted. This permits the motor to move under the influence of the driving winding only and to assume its normal speed. Further actuations of the detector by a vehicle will cause the memory relay to operate, which slows down the motor and causes said memory relay to be released upon the momentary opening of the stick circuit through cam 5A.

In the chart, in position 3, under cam 6, it will be noted that there is an interval for the latter part of said three position which overlaps into the beginning of position 4 in which cam 6 is not operated. When cam 6 is not operated, the contact 6A is in the position shown dotted, which engages the contact associated with said cam arm, and positively closes the stick-circuit of the memory relay. When cam arm 6A is thus associated with its contact, it will be observed that further periodic openings of the cam 5 will have absolutely no effect upon the stick circuit. The memory relay will be locked in, consequently, beyond the control of the periodic openings of the 5A cam arm and its associated contact.

In position 3, the latter part of said position finds cam 6 released, which period is known as the memory interval, which interval is that portion of the total memory period which is included in the cross-street green period. The total memory period is that portion of the cycle beginning with the last releasing of the memory relay, and terminating with the end of the cycle. In position 4, cam 6 is released during the beginning of the cycle, which release interval indicates the released time allotted for the relay E.

At the beginning of period 4, cam 7 releases which opens contact sets 7A-24 and transfers lights from G2 to A2. The relay E is thereby released, closing contact set 47-48, further rendering cam 5 ineffective. After the extension relay has had time to release, the cam 6 may again operate which separates cam arm 6A from its associated contact, thereby permitting the memory relay to be no longer under the control of cam 6, during the remainder of the cycle.

An actuation during memory interval, or the total memory period will cause an additional revolution of the cam shaft and a corresponding signaling cycle, since the memory relay will be locked in to keep the contact set 43-43" closed putting negative battery over conductor 45 on to conductors 56 and 57, to the driving motor, causing it to run irrespective of the condition of cam 1 and its associated contact set 1B-59.

Continuous operation independent of vehicle actuation

Heretofore, the apparatus has been described

as operating as a vehicle actuated system, but this is not necessary since by simply moving a double pole, double throw switch, to another position than that previously described, it is possible to have the system operate continuously and alternate the "go" signal and the corresponding "stop" signal with its intermediate caution periods from one street to the other, in a chain of connected signaling cycles. Two switches, 52 and 41, may be connected by an insulating member shown dotted as 69, which member may be moved to the right so that the switch blade 41 will be disconnected from contact 40 and the switch blade 52 will be moved from the contact 15 which is associated with 53 and said 52 blade will then be engaging contact 70. The circuit from all of the detectors which leads in to conductor 39 can no longer operate the memory relay. The switch 52, and its contact 71, now having been broken to open the circuit, to the reversing winding, and when switch 52 is moved to contact 70, battery is fed directly to the driving winding of the motor. In this respect a circuit may be traced from negative battery, over 20 conductor 45, armature 43, contact 43', conductor 51, contact-set 52-70, conductors 62, 63, 57 to driving winding of the motor, conductor 53 to positive battery. It will thus be seen that since no vehicle actuations can ever affect the signaling 25 apparatus and since the motor is continuously operated forwardly at one speed, the cam shaft will continuously rotate and in turn, cause the lights to be transferred from one position to another in their proper sequential relationship, to 30 enable traffic to move orderly.

Operation by surface car

A pair of contacts 72-72' are shown in parallel with the contact set 36-36', both sets of contacts, when closed, connecting negative battery to conductor 39, the contact set 72-72' is used to control the signaling system by a surface car 13. In operation, a shoe may be provided above the trolley wire, so that a passing surface car will engage that shoe to operate the signaling system. These shoes may be provided on opposite sides of the cross-street so that a trolley car coming from either direction, may operate the signal if this is desirable. In any case, it will be understood that any pair of contacts which are connected between negative battery and the conductor 39, will, at the proper time, control the signaling system. When a surface car wishes to cross the intersection, the trolley wheel proper, 75, will engage the shoe 74 which completes the circuit. When the surface car contacts 74-75 are closed, circuit may be traced from the source of energy 90, over conductor 77, through the contact-set 74-75, to conductor 76, resistor 81, conductor 80, relay 79, conductor 78, to the rails 91 upon which the surface car rides, back to the other side of the energy source. A ground is shown connected to the rails in Fig. 1. The resistor 81 may be located at any convenient place and may be of such value that when utilized in conjunction with the suitable relay 79, the resistor will limit the current flow to permit proper operation of the relay 79, to actuate the armature 72, to initiate a signal cycle.

While a specific arrangement is shown for the operation of the contact set 72-72', it is to be understood that any arrangement of parts may be used to ultimately cause a pair of contacts to be operated, which operation causes the initiation of a signaling cycle.

Pedestrian control

A push button shown as P, may be one of several which are placed in parallel and are used to initiate a signaling cycle by a pedestrian desiring to cross the highway. When the button is pressed by the pedestrian, a circuit is closed across the contacts 81—81', which puts negative battery on the winding of the coil TD and energizes same by getting positive battery over the conductor 82. The energization of the relay TD will attract the armature 83, associated with contact 84. Said contacts being in parallel with the detector 37—36', and trolley contact 72—72'. It will thus be seen that the attraction of 83 which engages contact 84 will close the circuit from negative battery to conductor 39, thereby initiating a signaling cycle. Relay TD will also attract armature 86, which engages contact 85, whereby a stick circuit for the relay TD will be traced from the negative battery over conductor 89, contact set 87—88, a second contact set 85—86, winding of TD, conductor 82, back to positive battery. This circuit will hold contacts 83—84 closed for a period of time depending on the time required for the relay TD to release, said relay TD being a time delay relay, which has a releasing time required for two operations of the cam 5. Relay Y is a restoring relay which unlocks relay TD, by interrupting the stick circuit due to the opening of the contact set 87—88, the armature 87 being responsive to energization of relay Y, is same as operated at the beginning of the cross-street green, or G2 period, and allows relay TD to respond to each impulse caused by closure of contact set 81—81' of push button P. This special pedestrian control circuit is utilized, since it is conventional to provide simply an initiating button parallel to the detector. It has been found in practice, that the time allowed for a vehicle to cross at the intersection, is frequently sufficient for a pedestrian to cross at the intersection, when the initiating contacts for the vehicle and pedestrian control are in parallel. This is permissive because the variation in time between that required by the vehicle and the pedestrian at the intersection, is usually just a few seconds. However, many intersections are so wide that the time discrepancy will vary from 5 to 20 seconds. The time delay relay, therefore, must be able to hold the 83—84 contact set closed for a time greater than that between two impulses of the 5A cam arm.

While specific details of the system have been herein shown and described, the invention is not confined thereto as changes and alterations may be and may become apparent to those skilled in the art without departing from the spirit thereof as defined by the appended claims.

Having thus described the invention, what I claim as new and desire to secure by Letters Patent of the United States, is

1. An automatic signaling system for a street intersection having a traffic signal for indicating "stop" and "go," switching means for operating

said signal, driving means for moving said switching means through a signal cycle, said driving means comprising energizable windings capable of simultaneously producing opposing torques of unequal degree to regulate forward the speed of said driving means, traffic actuable means for initiating a signal cycle by energizing one of said windings, and means caused by successive operations of said traffic actuable means for energizing a winding to produce a torque opposing said first mentioned winding to cause retardation of the driving means.

2. In a traffic signal for regulating the flow of traffic at intersection of streets, in combination, a traffic signal, switching means capable of controlling said traffic signal, a motor for said switching means, said motor having a forward driving and a reversing winding energizable simultaneously to reduce the forward speed of the motor caused by energization only of the forward driving winding, an energy source, means for associating said energy source with said forward driving and reversing windings, and traffic actuable means for operating said last named means.

3. In a traffic signal capable of operating through a signal cycle for regulating the flow of traffic at a street intersection, a traffic signal, switching means capable of controlling said traffic signal, a motor for operating said switching means, said motor having a driving winding for causing rotation of the motor in one direction and a reversing winding simultaneously energizable with the driving winding to produce a torque in the opposite direction to reduce the forward speed of the motor caused by energization of the driving winding only, an energy source, means for connecting said energy source with said driving and reversing windings, and traffic actuable means for initiating operation of the signal cycle.

4. A traffic signal capable of operating through a signal cycle for regulating the flow of traffic at intersecting streets, in combination, a traffic signal for indicating "stop" and "go," switching means for causing operation of said traffic signal, speed control means for operating said switching means, said speed control means having a plurality of windings certain of which are capable of producing a torque in a direction of rotation opposite to certain of said other windings to produce a retarding effect upon said speed control means, and traffic actuable means for initiating the signal cycle.

5. A traffic signal for regulating the flow of traffic for intersecting streets, a traffic signal, switching means connected to said traffic signal to cause operation thereof through a signal cycle, control means for operating said switching means which control means have windings capable of simultaneously producing opposing torques to retard the forward motion of said control means, and traffic actuable means for initiating the signal cycle.
